(57) **CLAIM**

The ornamental design for a mobile device stand as shown and described.

DESCRIPTION

FIG. 1 is a perspective view of a mobile device stand showing my new design.

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

Broken lines illustrate portions of the mobile device stand that form no part of the claimed design.
